(57) **CLAIM**

The ornamental design for a blank firearm round, as shown and described.

DESCRIPTION

FIG. 1 is a right-side view of a first embodiment of a blank firearm round, showing my new design, the left-side, top, and bottom views of this embodiment being the same; FIG. 2 is a front end of the embodiment of FIG. 1.

FIG. 3 is a rear end view of the embodiment of FIG. 1. FIG. 4 is a front-right perspective view of the embodiment of FIG. 1.

FIG. 5 is a front-top perspective view of the embodiment of FIG. 1.

FIG. 6 is a rear-left perspective of the embodiment of FIG. 1.

FIG. 7 is a rear-bottom perspective view of the embodiment of FIG. 1.

FIG. 8 is a right-side view of a second embodiment of a blank firearm round showing my new design, the left side view of this embodiment being the same;

FIG. 9 is a top view of the embodiment of FIG. 8, the bottom view being the same.

FIG. 10 is a front end view of the embodiment of FIG. 8.

FIG. 11 is a rear end view of the embodiment of FIG. 8.

FIG. 12 is a front-right perspective view of the embodiment of FIG. 8.

FIG. 13 is a front-top perspective view of the embodiment of FIG. 8.

FIG. 14 is a rear-left perspective view of the embodiment of FIG. 8; and,

FIG. 15 is a rear-bottom perspective of the embodiment of FIG. 8.
